Attorney, Agent, or Firm—Dougherty & Associates[57] **CLAIM**

The ornamental design for a soundhole cover for guitar, as shown and described.

DESCRIPTION

FIG. 1 is a top perspective view of a soundhole cover for guitar, showing my new design;

FIG. 2 is a top view thereof;

FIG. 3 is a bottom view thereof;

FIG. 4 is a front view thereof, the rear view, the right side view and the left side view being identical; and,

FIG. 5 is a reduced top view of the soundhole cover being installed on a guitar, the broken lines are shown for illustrative purposes only and form no part of the claimed design.
